WO DM/057386 * 10/2001

Primary Examiner — Barbara Fox

(57) **CLAIM**

The ornamental design for a handheld device, as shown and described.

DESCRIPTION

FIG. 1 is a front perspective view of a first embodiment of a handheld device showing my new design, in which there are two notches at the top;

FIG. 2 is a rear perspective view of the first the embodiment of my new design;

FIG. 3 is a front elevational view of the first the embodiment of my new design;

FIG. 4 is a rear elevational view of the first the embodiment of my new design;

FIG. 5 is a left side elevational view of the first the embodiment of my new design;

FIG. 6 is a right side elevational view of the first the embodiment of my new design;

FIG. 7 is a top plan view of the first the embodiment of my new design;

FIG. 8 is a bottom plan view of the first the embodiment of my new design;

FIG. 9 is a front perspective view of a second embodiment of a handheld device showing my new design, in which there is one notch at the top;

FIG. 10 is a rear perspective view of the second embodiment of my new design;

FIG. 11 is a rear elevational view of the second embodiment of my new design; and,

FIG. 12 is a top plan view of the second embodiment of my new design.

The views of the second embodiment that are not illustrated are identical to those of the first embodiment.
